LEO BANNEY, OF NEW YORK, N. Y.

HYDRAULIC TOY

Application filed July 5, 1929, Serial No. 376,242. Renewed November 23, 1932.

This invention relates to toys, more particularly to hydraulic toys which operate as a result of movement of a stream of water or other liquid.

5 The most popular types of toy nowadays are those which attain realism by the active performance of some function. In the case of hydraulic toys there are and may be designed a vast number of species of toy which 10 may be made realistic and entertaining provided there is available some satisfactory means for elevating or circulating or pumping a stream of water or other liquid. The primary object of my invention is to fulfill 15 this need, and to provide an exceedingly simple and economical means for causing the desired movement or circulation of a liquid from, say, a relatively low level to a relatively high level, and to this end my invention includes expelling a stream of gas bubbles into the liquid at the low level. In this manner blocks or chunks of the liquid are trapped between successive rising bubbles of the gas, and the liquid is thereby put into motion. From another viewpoint we may say that the column of liquid which is lightened by the gas bubbles is raised by the surrounding body of denser liquid.

More specifically, I have invented a toy air 20 lift pump, in which a stream of water is caused to flow through a conduit by feeding air bubbles into the conduit. In many cases the conduit is relatively upright, and only one end thereof is immersed in the water, and 25 in such case the air bubbles are fed into the conduit at a point below the water level, and most simply, at the foot or immersed end of the conduit.

40 A further object of my invention is to improve the operation of such a toy pump, and with this in view I have found it expedient to provide the lower or foot end of the conduit with an enlarged mouth or funnel-shaped opening, into which the air supply is 45 introduced.

A still further object of my invention is to provide an appropriately simple and economical source of air supply, which I do by the use of an inflatable elastic air bladder, 50 much like a toy balloon, which may be in-

flated by the user at the time the toy is to be placed in operation. This incidentally simplifies a problem which arises with those forms of toy which are propelled or swim along the surface of a body of water, for in such cases the air bladder also floats on the surface of the water and is simply towed along by the toy, until the air supply is exhausted. This bladder may be made relatively elongated and painted and decorated to 55 resemble a sail boat or other floating object.

To the accomplishment of the foregoing and such other objects as will hereinafter appear, my invention consists in the pump and toy elements and their relation one to the other as hereinafter are more particularly described in the specification and sought to be defined in the claims. The specification is accompanied by drawings in which:

Fig. 1 illustrates my invention as applied 70 to a toy spouting whale;

Fig. 2 shows a modified form of toy whale arranged to swim as well as to spout;

Fig. 2a is a detail of a pinch cock employed in the toy illustrated in Fig. 2;

Fig. 3 illustrates a toy stern paddle wheel steam boat;

Fig. 4 represents a toy mill wheel;

Fig. 5 shows a miniature cascade fountain;

Fig. 6 is a side elevation of a toy ducking 80 wheel;

Fig. 7 is an end elevation thereof;

Fig. 8 is a section through a toy coffee percolator; and

Fig. 9 represents a spouting floating frog.

Referring to Fig. 1, there is a floating toy 2, preferably simulating a whale, which is provided with an air lift pump 4, to which there is connected a suitable gas or air supply source 6.

The toy 2 may conveniently and economically be manufactured of hollow celluloid or like material, in a manner which is commonly employed in the manufacture of inactive floating toys. With such a construction the apertures through which the pump is inserted are sealed to prevent leakage of water into the body of the toy.

The pump 4 consists of an upright riser 100 or conduit 8, which need not be, but prefer-

ably is, provided with an enlarged mouth or inverted funnel-shaped end 10. In case the pump mechanism is insufficient in weight to have the desired ballasting effect it may be 5 additionally weighted, as is indicated by the annular weight 12.

The air nozzle 14 extends into the enlargement 10 and is provided with an air discharge opening 16. The protruding end of 10 the nozzle 14 acts as a nipple over which one end of a flexible connecting tube 20 is connected.

The source 6 most simply consists of an inflatable elastic sac or bladder resembling a 15 rubber toy balloon, blown full of air through a neck 22, over which the other end of the interconnecting tube 20 may thereafter be slipped.

The riser 8 of the pump may be inclined 20 slightly to the rear, as shown, if it is desired to obtain a propulsive effect due to the reaction of the force required to shoot the expelled stream or chunks of water backward.

In operation, air discharged from the 25 source 6 escapes through the opening 16 inside of the enlargement 10 at the foot of the conduit 8, and the resulting bubbles of air rise up the conduit. Chunks or blocks of water are trapped therebetween, and are carried upward, resulting in a stream of water 30 being expelled or spouted from the upper end of the riser 8, which is appropriately located to represent the blow hole of the whale, the water being expelled with considerable force 35 and height, even in the case of relatively tiny celluloid toys.

The modified form of spouting whale illustrated in Fig. 2 is similar to that shown in Fig. 1 in comprising a floating air tight whale 40 body 2, to which is sealed an air lift pump 4 comprising an upright conduit 8, provided with an enlargement 10 and a ballast weight 12. The air nozzle 14 in this case is illustrated as having its discharge opening 16 45 pointed downwardly, for I have found that this does not at all adversely affect the operation of the pump. The present form of toy also differs in being equipped with a rearwardly pointed discharge opening 24, expansion of air through which serves to propel 50 the toy along the surface of the water. In order to make the use of the propulsion or swimming feature of the toy optional the nozzle 24 may be equipped with an extension 55 26, consisting of a short piece of rubber tubing, and a throttle or pinch cock element 28, which, as is best shown in Fig. 2a, is formed with a triangular or wedge shaped opening 30, which may be used to pinch the tube 26 60 and thereby prevent escape of air therethrough.

The foregoing propulsion means has been selected merely by way of illustration, for any propulsion means, particularly if responsive to air supplied thereto, may equally

well be employed. An example of such a propulsion means, which operates by the pressure of rising expanding air bubbles on an inclined immersed surface, is fully described in my copending application Ser. No. 376,244, 70 filed concurrently herewith, and also is exceedingly well adapted for use with a toy such as is here described.

The air supply tube 20 is slipped over a nipple 22, inserted in the tail of the toy, while 75 the water pump 4 and the propulsion nozzle 24 are both supplied with air from the body of the toy, in a manner which is obvious from an inspection of the drawings. A source of air supply is connected to the other end of the 80 tube 20, as before.

Attention is now directed to the form of the invention shown in Fig. 3, which represents a stern paddle wheel river steam boat. The boat consists of a hull 32, which, if necessary, 85 may be suitably ballasted by a weighted keel 34. The boat also carries a pump arrangement 4, consisting of a riser or conduit 38, which in this case is illustrated as being tapered for part of its length, while to the 90 mouth or enlarged end thereof an air nozzle 40 is fitted. An air supply tube 20 is run from the nozzle 40 to a suitable source of air, which may be an inflated elastic bladder, such as the bladder 6 described in connection with 95 Fig. 1.

The pump 4 serves to expel a stream of water, mixed with air bubbles, from the trailing end of the conduit 38, which in this case is located at or beneath the surface of the 100 water, and this effect may alone be used to propel the boat along the surface of the water. During its travel it may tow the air sac 6 along with it.

In order to improve the appearance of the 105 toy, and increase the operating efficiency thereof, I mount a freely rotatable paddle wheel 42 in a yoke 44 fixed to the stern of the hull 32. The paddles of the wheel 42 are located in the path of the stream expelled from 110 the conduit 38. In this manner the paddle wheel is caused to revolve, which enhances the realism of the operation of the toy, and, at the same time, owing to the breadth of the individual paddle wheels, the energy of the 115 escaping stream of water and air is more efficiently transferred to the main body of water and utilized to propel the ship along the surface thereof.

In Fig. 4 I have illustrated a toy which 120 simulates an old mill wheel. There is a mill house 50, on which is mounted a mill wheel or bucket wheel 52. The mill house and wheel may be mounted over a self contained reservoir or tray 54, or, if desired, may be arranged 125 to float on the surface of a large body of water. The former arrangement is here illustrated, the reservoir or tray 54 being filled with water, which is utilized in continuous circulation when the toy is in operation, so 130

that the available water is not exhausted and in permitting more rapid rotation of the need not be replenished.

As before, the toy is provided with a pump system 4, comprising in this case an upright conduit provided with a return bend 56, bringing the discharge end thereof over the buckets of the mill wheel 52. The entrant end of the conduit is provided with an enlarged foot 58, which acts also as a pedestal to help support the conduit. The pump is provided with an air nozzle 60, to which air is fed through a tube 20 from any suitable source, as has been before outlined.

In operation, the discharged bubbles of air cause a stream of water to flow through the conduit and this stream of water falls upon the buckets of the mill wheel 52 and causes the latter to revolve. The exhaust water is discharged from the buckets back into the reservoir 54, where it may again be elevated to rotate the mill wheel, so long as the air supply is maintained.

Fig. 5 illustrates how my novel toy pump may be applied to a miniature fountain. In this case the liquid which is pumped up through the riser 62 is discharged as a spray fountain from the upper end thereof, the liquid thereafter falling back into the reservoir 64. In order to improve the display and beauty of the fountain the riser 62 may be provided with a series of trays 66, of successively increasing diameter, so that the fountain liquid is returned to the reservoir only after a series of interrupted drops or cascades.

This device may be used as a toy, or it may be used for decorative purposes. The liquid may be a perfume, instead of plain water, at the time of an appropriate social occasion.

Attention is next directed to the toy ducking wheel illustrated in Figs. 6 and 7. This consists of a main body or wheel 70, which may be spherical in shape, as illustrated, and pivoted for free rotation on an axis 72, the ends of which are bent to form integrally therewith a substructure or suspended yoke 74. On the periphery of the wheel 70 there are mounted a series of blades or vanes 76, and a series of small figures, 78, simulating human beings or animals or both. The wheel 70 is preferably made by cementing together two semi-circular halves of celluloid-like material, and in such case the figures 78 may be formed integrally therewith, the dividing seam between the halves passing through the center of each of the figures, as is indicated in Fig. 7.

The toy floats on the surface of the water, in either of two positions, one with the water level below the axis, in which case no water is inside of the wheel, and the other with the axis 72 at or slightly below the level of the water, which is the position assumed when water is permitted to enter inside the wheel. The latter position is slightly advantageous

in permitting more rapid rotation of the wheel.

To the yoke 74 there is fixed a conduit 80, and an air nozzle 82, directed thereinto. Air is supplied to the nozzle 82 by a flexible rubber tube 20. A stream of water and air bubbles is thus directed upwardly and impinges upon the blades or vanes 76, and causes the wheel 70 to revolve, thereby ducking the toy figures 78 successively into the main body of water, to the great amusement of the child operating the toy. At the same time, due to the engagement of the paddles 76 with the main body of water there is a gradual travel of the toy through the water, which is not hindered if the source of air supply is an elastic bladder such as has already been mentioned, for this may be towed along with the toy.

I find that the water and air circulation may be used directly to operate the toy successfully even if the conduit 80 is omitted, and I therefore wish it to be understood that the use of the conduit 80 is optional.

In Fig. 8 I have illustrated how my invention may be applied to actuate a toy coffee percolator. This toy comprises an external body portion 90 provided, as is customary, with a spout 92, a handle 94, and a cover 96, the dome 98 of which is made of glass, all in simulation of a real coffee percolator. Within the percolator there is set an upright conduit or riser 100 which carries at its upper extremity a tray or open vessel 102, having a strainer or sieve-like bottom 103, which may be used to carry coffee or any coffee resembling substance. The bottom of the riser 100 is affixed to a base or support 104, the bottom edge of which is provided with openings or recesses 106 so as to be in flow communication with the main body of liquid 108 which is carried by the percolator body 90.

Air is supplied through an air supply tube 20 to a nipple 110, which passes through appropriate perforations in the percolator body 90 and the coffee tray 102. To the inner end of the nipple 110 there is attached a tube 112 which is connected to a nozzle 114 leading inside of the enlarged base 104. In operation the bubbles of air admitted beneath the base 104 rise up the conduit 100 and carry with them blocks of water which are sprayed in intermittent fashion against the glass dome 98, the water thereafter falling through the tray 102 and whatever substance may be carried thereby, and finally returning to the main body of liquid 108 through the strainer or sieve-like bottom 103 of the tray 102.

The spouting or spluttering of the contained fluid may be viewed through the glass dome 98, so that the toy is realistic in its operation, and yet is entirely incapable of burning or injuring the child using the same, as might be the case were the action obtained by boiling, as in a real percolator. The water may become colored from a coloring sub-

stance carried in the tray 102, and finally may be poured out of the spout 92 when the "coffee" has been prepared to the desired "strength" or color.

- 5 In Fig. 9 I show a modified toy in combination with a modified source of air supply. The toy 120 is a floating toy which simulates a frog. Sealed into the body thereof is a riser or conduit 122, the upper end 124 of which is bent and terminates at the mouth of the frog. The lower end of the riser is fitted with an enlarged foot 124, into which leads an air nipple 126. A ballast weight 128 may be provided, and is so positioned along the riser 122 as to keep the toy in desired position or balance on the surface of the water. In operation, if a relatively slow supply of air is applied to the toy, water is ejected from the mouth thereof in spurts as though the frog were spitting during its swim. The reaction to the expulsion of the water from the mouth of the toy tends to move the toy backward and this movement may be increased by increasing the rapidity of the air supply. If the rate of air supply is still further increased the air may be made to accumulate in the enlarged foot 124 faster than it is relieved by discharge through the riser 122, and this so lightens or buoys upward the toy 120 that the latter may be made to rise upward out of the water with a sort of hopping movement, after which the toy again settles onto the water, owing to relief or discharge of the excess air from beneath the periphery of the enlarged foot 124. Air will then again accumulate beneath the foot, and the operation be repeated in continuous sequence. The various resulting movements, together with the expulsion of water from the mouth of the toy, all lend to realistic and amusing operation.

In this case I have illustrated a modified form of air bladder or balloon, consisting of an elastic rubber bladder 130 which is made relatively elongated in configuration, and which is provided with a discharge nipple 132 at one end thereof, and an inlet nipple 134 at the other end thereof. The discharge nipple 132 may be a simple neck or outlet arranged to have the air supply tube 136 fitted over the end thereof. The inlet nipple 134 is provided with a valve, so that the bladder may be inflated by blowing air therethrough, but the air does not thereafter escape from the nipple 134 but must flow out of the discharge nipple 132.

The inlet nipple 134, while intended for direct inflation, is nevertheless made small in diameter so as to accommodate an interconnecting tube, such as the tube 136, in case it is desired to connect several of the air supply bladders in series. In such case it is merely necessary to connect the discharge nipple of the additional bladder to the inlet

nipple of the next bladder through an interconnecting tube of suitable length.

Another desirable feature about the present air supply unit is that it is appropriately painted and colored to resemble a subject which might be found on the surface of the water. In the present case, for example, the sides of the bladder are painted to resemble a sail boat. The lower seam of the bladder is provided with a fin 138, most simply formed by cementing the edges of the bladder together. To the fin 138 a slight ballast weight 140 may be added in order to keep the bladder in proper position relative to the features painted on the surface thereof. It goes without saying that these bladders may be given different shapes and may be painted to resemble various fish, animals, boats, or even, say, a floating island.

It will be understood that the foregoing forms of toy are merely representative, and not exclusive, for many others may readily be suggested, such as a flowing spring, or an artesian well, or a toy water fall. Also, the fountain may be modified to represent a frog or other animal expelling water from its mouth. A toy steam boat may be constructed which combines the features of the arrangements shown in Figs. 3 and 4 of the present disclosure, that is to say, water may be elevated by my novel air lift pump and caused to drop upon the paddles of the stern paddle wheel, the wheel being caused to rotate by gravity, and rotation of the wheel serving to propel the boat through the water. The toy steam boat illustrated in Fig. 3 may also be modified by the use of a pair of side paddle wheels instead of a single stern wheel. In such case the riser is divided into two branches in the form of a Y, a portion of the mixed air and water stream flowing through either branch. The ends of the branches are each directed against the paddle wheel blades in a manner similar to that employed in the case of the stern paddle wheel illustrated in Fig. 3.

In operating the air lift pump it is desirable to have the level of the water surrounding the riser as high as possible, preferably almost as high as the riser itself, and at least about one quarter as high as the riser. The riser should be moderately small in diameter so that chunks or blocks of water will be efficiently trapped between successive air bubbles, the air bubbles serving to fill the riser completely in a transverse direction. In other words, if the riser is made very much too large in diameter there is a tendency for the air bubbles to rise through the body of water contained within the riser without putting this water completely into motion, the engagement then being practically only that of friction.

By employing appropriately small sized interconnecting and/or discharge tubes the

air supply may be kept up for a relatively long period of time even though it be obtained from a simple inflatable bladder. Due to the back pressure of the water the air is expelled and consumed only in intermittent bubbles. With practically no precaution at all the toys may be run for at least several minutes, and by using two air bladders in series and smaller bore tubing I have operated these toys continuously for about an hour and a quarter.

For convenience in coupling the tube to the toys the nipple may be left on the tube and inserted with a tight fit into the toys.

15 The mode of operation of my novel toys will be understood from the foregoing description, and in general, consists in putting a liquid into motion or circulation, or in elevating it from a relatively low to a relatively high level, by emitting or expelling bubbles of a gas into the liquid. The liquid ordinarily is water, but need not be so, and the gas ordinarily is air, but also need not be so, as for example, if a tank of compressed 25 nitrogen or oxygen or other gas is available.

It will be apparent that while I have shown and described my invention in the preferred forms, many changes and modifications may be made in the structures disclosed without departing from the spirit of the invention, 30 defined in the following claims.

I claim:

1. A toy comprising a floating toy member, means to actuate the same including a relatively upright conduit the lower end of which is immersed in the body of water on which the toy floats, an enlarged mouth at the lower end thereof, an inflatable elastic air bladder also adapted to float on the body of water, and a flexible tube leading from the bladder to the enlarged mouth of the conduit in order to feed a continuous supply of air bubbles thereto during the deflation of the bladder and thereby pump water upwardly 45 through the conduit for actuating the toy.

2. A toy comprising a floating toy member, means to propel the same including a relatively upright but at least partially inclined conduit the lower end of which is immersed in the body of water on which the toy floats, an enlarged mouth at the lower end thereof, an inflatable elastic air bladder also adapted to float on the body of water, and a flexible tube leading from the bladder to the enlarged mouth of the conduit in order to feed a continuous supply of air bubbles thereto during the deflation of the bladder and thereby pump water upwardly through the conduit for propelling the toy.

60 3. A toy comprising a rotatable toy member, means to rotate the same including a relatively upright conduit the lower end of which is immersed in water, an enlarged mouth at the lower end thereof, an inflatable elastic air bladder, and a tube leading from

the bladder to the enlarged mouth of the conduit in order to feed a continuous supply of air bubbles thereto during the deflation of the bladder and thereby pump water upwardly through the conduit for rotating the 70 toy member.

4. A floating toy comprising a rotatable toy member, means to rotate the same including a relatively upright conduit the lower end of which is immersed in the body of water on which the toy floats, an enlarged mouth at the lower end thereof, an inflatable elastic air bladder also adapted to float on the body of water, and a flexible tube leading from the bladder to the enlarged mouth of the conduit in order to feed a continuous supply of air bubbles thereto during the deflation of the bladder and thereby pump water upwardly through the conduit for rotating the 75 toy member.

5. A floating toy comprising a rotatable member for propelling the toy in the water, means to rotate the said member including a relatively upright but at least partially inclined conduit the lower end of which is immersed in water, an enlarged mouth at the lower end thereof, an inflatable elastic air bladder, and a flexible tube leading from the bladder to the enlarged mouth of the conduit in order to feed a continuous supply of air bubbles thereto during the deflation of the bladder and thereby pump water upwardly 80 through the conduit for rotating the 85 toy member.

6. A floating toy comprising a rotatable member for propelling the toy in the body of water on which it floats, means to rotate the said member including a generally upright conduit the lower end of which is immersed in the said body of water, an enlarged mouth at the lower end thereof, a source of continuous air supply, and a flexible tube leading from the source to the enlarged mouth of the conduit in order to feed a continuous supply of air bubbles thereto and thereby pump water upwardly through the conduit for rotating the rotatable member, and thereby propelling the toy.

7. A toy comprising a floating toy member, means to propel the same including a generally upright but at least partially inclined conduit the lower end of which is immersed in the body of water on which the toy floats, an enlarged mouth at the lower end thereof, a source of continuous air supply, and a flexible tube leading from the source to the enlarged mouth of the conduit in order to feed a continuous supply of air bubbles thereto and thereby pump water upwardly through the conduit for propelling the toy.

8. A toy comprising a floating toy member simulating an aquatic animal, means to actuate the same including a relatively upright conduit the lower end of which is im-

- mersed in the body of water on which the toy floats, and the upper end of which terminates near the head of the animal, an enlarged mouth at the lower end of said conduit, an 5 inflatable elastic air bladder also adapted to float on the body of water, and a flexible tube leading from the bladder to the enlarged mouth of the conduit in order to feed a continuous supply of air bubbles thereto during 10 the deflation of the bladder and thereby pumping water upwardly through the conduit and apparently expelling the same from the animal.
9. A toy comprising a floating toy member simulating an aquatic animal, means to 15 propel the same including a generally upright but at least partially inclined conduit the lower end of which is immersed in the body of water on which the toy floats, and 20 the inclined upper end of which terminates near the head of the animal, an enlarged mouth at the lower end of said conduit, a source of continuous air supply, and a flexible tube leading from the source to the enlarged mouth of the conduit in order to feed a continuous supply of air bubbles thereto, and thereby pumping water upwardly through the conduit and apparently expelling the same from the animal in a realistic 25 manner, and at the same time propelling the animal.
10. A mill toy comprising a rotatable water wheel, means generally simulating a mill house for rotatably supporting said wheel, 30 and means to rotate the same including a relatively upright conduit the lower end of which is immersed in a body of water, and the upper end of which terminates at a point adjacent the periphery of the water wheel, an 35 enlarged mouth at the lower end of said conduit, an inflatable elastic air bladder, and a tube leading from the bladder to the enlarged mouth of the conduit in order to feed a continuous supply of air bubbles thereto during the deflation of the bladder, and thereby pumping water upwardly through the conduit and delivering the same to and causing rotation of the water wheel.
11. A boat toy comprising a floating toy 40 simulating a boat, a rotatable paddle wheel mounted on said boat, and means to rotate the same and propel the boat including a relatively upright conduit the lower end of which is immersed in the body of water on 45 which the boat is travelling, and the upper end of which terminates adjacent the paddle wheel, an enlarged mouth at the lower end of said conduit, a source of continuous air supply, and a flexible tube leading from the 50 source to the enlarged mouth of the conduit in order to feed a continuous supply of air bubbles thereto and thereby pump water upwardly through the conduit for rotating the paddle wheel and propelling the boat.
- 60 12. A boat toy comprising a floating toy 55 simulating a boat, a rotatable paddle wheel mounted on said boat, and means to rotate the same and propel the boat including a relatively upright conduit the lower end of which is immersed in the body of water on 65 which the boat is travelling, and the upper end of which terminates adjacent the paddle wheel, an enlarged mouth at the lower end of said conduit, a source of continuous air supply, and a flexible tube leading from the 70 source to the enlarged mouth of the conduit in order to feed a continuous supply of air bubbles thereto and thereby pump water upwardly through the conduit for rotating the paddle wheel and propelling the boat.
- 75 80 85 90 95 100 105 110 115 120 125 130
- simulating a boat, a rotatable paddle wheel mounted on said boat, and means to rotate the same and propel the boat including a relatively upright conduit the lower end of which is immersed in the body of water on which the boat is travelling, and the upper end of which terminates adjacent the paddle wheel, an enlarged mouth at the lower end of said conduit, an inflatable elastic air bladder also adapted to float on the body of water, and a flexible tube leading from the bladder to the enlarged mouth of the conduit in order to feed a continuous supply of air bubbles thereto during deflation of the bladder and thereby pump water upwardly through the conduit for rotating the paddle wheel and propelling the boat.
- Signed at New York in the county of New York and State of New York this 19th day of June, A. D. 1929.
- LEO RANNEY.
